US00D574347S

(12) **United States Design Patent**
Lee et al.

(10) **Patent No.:** US D574,347 S
(45) **Date of Patent:** ** Aug. 5, 2008

(54) **PORTABLE PHONE**

(75) Inventors: **Woo-Seok Lee**, Gunpo-si (KR); **Jin-Soo Kim**, Yongin-si (KR); **Nam-Mi Kim**, Seoul (KR); **Chang-Hwan Hwang**, Goyang-si (KR)

(73) Assignee: **Samsung Electronics Co., Ltd.**, Suwon-Si (KR)

(**) Term: **14 Years**

(21) Appl. No.: **29/266,435**

(22) Filed: **Sep. 21, 2006**

(30) **Foreign Application Priority Data**

Mar. 24, 2006 (KR) 30-2006-0011023

(51) **LOC (8) Cl.** **14-03**

(52) **U.S. Cl.** **D14/138**

(58) **Field of Classification Search** D14/137-138, D14/147-148, 156, 218, 247-248, 341-347, D14/496; D16/208; D21/329, 331, 333, D21/517; 348/14.01-14.02; 361/814; 379/433.01-433.13; 455/90.3, 556.1-556.2, 566, 575.1, 575.3, 455/575.4

See application file for complete search history.
